(57) **CLAIM**

The ornamental design for a water bottle dispenser, as shown and described.

DESCRIPTION

FIG. 1 is a front perspective view of a water bottle dispenser, showing my new design;

FIG. 2 is a right side elevation view thereof;

FIG. 3 is a left elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front perspective view of the water bottle dispenser, shown in use condition.

The broken lines in the drawing views represent unclaimed portions of a water bottle dispenser, which are included for the purpose of illustrating unclaimed environment only, and form no part of the claimed design.
